LUDWIG KOLLEBOHM, OF HAGEN, GERMANY, ASSIGNOR OF ONE-HALF TO DEUTSCHE BABCOCK- UND WILCOX-DAMPFKESSEL-WERKE A. G., OF OBERHAUSEN/RHINELAND, GERMANY

IMPACT MILL

Application filed February 18, 1929, Serial No. 340,887, and in Germany February 23, 1928.

In the known so-called impact mills, the material to be disintegrated is thrown against an impact surface by a current of compressed air, and thereby disintegrated. Since the material to be disintegrated must be flung against the impact surface with considerable force it is necessary to introduce the current of air that moves the said material at a considerable pressure, so that the entire vessel in which the grinding operation proceeds is subjected to pressure. Now it has been found that the disintegrating action is checked to a remarkable extent in a space subjected to pressure, since the air which is subjected to pressure produces a cushioning effect, and obstructs the action very greatly, particularly for fine gravel.

According to the present invention this disadvantage of the impact mills hitherto known is obviated by evacuating the interior by means of a suction blower and maintaining a vacuum therein preferably amounting to from 50 to 80 millimetres of water. The energy of the current of compressed air that moves the material to be ground then produces its full effect, without the interior of the grinding apparatus being exposed to a pressure that would obstruct the disintegration of the material.

According to the invention the effectiveness of this disintegrating apparatus is substantially enhanced by a special construction of the hollow body that guides the current of air carrying the material to the impact surface facing the said hollow body, and of the grinding casing. The hollow body, which guides in its interior the mixture of compressed air and material to be ground, at a high velocity, forms at the same time, by appropriate construction of its outer walls, the internal closure of the circular conically and spirally tapering suction space for the material, while a suitably shaped grinding casing forms the external closure. The impact surface has a concave curvature like that of a hollow cone, a paraboloid or the like, whereby the result is obtained that the material leaving the conically flaring hollow body strikes perpendicularly against the impact surface and is thrown back, whereby the wear

of the impact surface is effectually diminished. Furthermore by the mutual impact of the particles of material approaching and leaving the impact surface the disintegration is assisted.

By a central arrangement of the inlet for the supply of material, a uniform charging of the mill throughout its periphery is obtained, and an intimate mixing of the fresh material with the material that is already in circulation and partially disintegrated, whereby a preliminary disintegration is already initiated. The grinding casing contains screened apertures for a supply of secondary air, which produces a readily transportable mixture of ground material and air. In the lower portion, tangentially entering scavenging air pipes serve effectually to obviate stoppages.

Various constructional forms of the invention are illustrated by way of example in the accompanying drawings, in which

Figure 1 shows in sectional elevation an impact mill according to the invention,

Figure 2 shows on a smaller scale a second constructional form in section,

Figure 3 illustrates the explanation of the method of working of the impact mill,

Figure 4 is a view similar to Figure 2 of an impact mill according to Figure 2 with an increased output.

Figure 5 is a section on the line 5—5 in Fig. 4, and Figure 6 shows a further constructional form of the impact mill according to the invention.

In the impact mill according to the invention illustrated in Figure 1, the material to be ground is supplied through an inlet pipe *k* with a double sluice *e* to the casing *a* of the mill, and slides down the downwardly tapering hopper-like wall of the casing to the lowest point of the mill, where compressed air is introduced through a nozzle *d*. At a suitable height above this nozzle is located a guiding and scattering body *b*, by which the current of compressed air, carrying the material to be ground, is thrown against an impact plate *c*. The disintegration of the material there takes place in a known manner. The impact plate itself is stationary,

but the height thereof is adjustable. Preferably above the impact plate there is connected to the casing a a suction blower g , by which a partial vacuum is sustained in the casing, amounting for instance to from 50 to 80 millimetres of water.

At the same time the blower g sucks the already sufficiently disintegrated material out, while the constituents that are not sufficiently disintegrated drop off the plate c in the manner indicated, and then slide down the funnel-shaped walls of the casing a and are again thrown against the impact plate by the current of compressed air.

15 By employing hot air for driving the material, it is possible during the grinding process to dry the material at the same time.

In the constructional form of the invention according to Figure 2, there is likewise 20 provided in the casing a' an upwardly flaring guiding and scattering body b' serving to supply the material to be ground. Above this guiding and scattering body b' is arranged the impact body c' , which has a concave curvature facing the mouthpiece of the scattering body b' . The material entering at k' is here distributed conically over the impact body c' and passes into the suction space m . By the screened secondary air supply 25 ducts i , the material to be ground is thoroughly mixed with air. The mixture of material and air passes into the nozzle-like lower portion of the guiding and scattering body b' , and is brought to a high velocity in the 30 cavity n by the compressed air supply d' and is thrown in jet form against the hemispherical impact surface c' , in such a manner that the individual particles meet the impact surface perpendicularly. Under these circumstances a disintegration will occur the more 35 energetically, as the particles of material approaching and leaving the impact plate are whirled together and disintegrate one another by mutual friction.

40 45 The particles of material retain the high velocity imparted to them until they strike the impact plate, while the compressed air in the guiding body b' in consequence of its diffuser-like form, gradually loses its velocity, so that the separation of the sufficiently disintegrated material is thereby facilitated. By the exhauster connected to the mill casing a' at e' , there is produced in the mill a rarefaction of air, which effects first a sifting 50 55 of the entering material and then a sifting of the material thrown off by the impact surface, while all the still insufficiently disintegrated particles of the ground material pass into the space m , where the pressure is below atmospheric, and are reintroduced into the circuit.

The compressed air nozzle d' the guiding and scattering body b' , and the impact body c' are according to the invention adjustably 60 65 arranged in the casing a' , so that they can be

adjusted according to the nature of the material to be treated.

Figure 3 enables the method of operation of the jet-like splitting of the material conveyed to be better understood.

70 Figures 4 and 5 show in sectional elevation and plan respectively the construction of the impact mill according to Figure 2 for higher outputs, in such a way that instead of the single guiding and scattering body b shown in Figure 1, a plurality of such bodies b_2 are provided, so that here a plurality of guiding ducts n_1 acting in the manner hereinbefore described are present, to which there correspond a common impact surface or a plurality of associated impact surfaces, whereby the output admits of being considerably increased in a casing which is only slightly larger. Each of the compressed air pipes d_2 pertaining to the individual guiding and scattering bodies is capable of being separately shut off, thereby enabling the output to be regulated within wide limits. In order to obviate stoppages at the bottom of the casing a , compressed air can be introduced from time to time through tangentially opening compressed air pipes h_1 provided with shut-off members, for the purpose of eliminating if necessary deposits of material. Secondary air is supplied through the screened ducts i_1, i_2 .

80 85 90 95 100 105 110 115 120 125 130 Figure 6 shows a modified constructional form of the invention, wherein instead of compressed air, air delivered under pressure by a high pressure fan or a rotary blower is employed. In this case the pressure connection of the blower f is introduced into the bottom of the grinding casing a_3 so that this pressure connection wholly or (as illustrated) partly replaces the guiding and scattering body b_3 at the same time. Between the pressure connection f and the guiding body b_3 a rarefaction of air is produced in the circular slot g introduced in the direction of pressure, and the material is thereby drawn out by suction and carried away according to Figs. 1 and 2. The disintegrating process is the same as in the mills according to Figs. 1 to 3 previously described.

What I claim is:—

1. An impact mill for disintegrating solid material, comprising a casing, an impact plate in the casing, a nozzle adapted to admit a jet of compressed air into the casing to throw material that has been introduced into the casing against the said impact plate, a suction blower adapted to maintain a pressure below atmospheric pressure in the casing, and screened inlets for admitting secondary air to the casing to mix with the material that is being disintegrated.

2. An impact mill for disintegrating solid material, comprising a casing, an impact plate in the casing, a nozzle adapted to admit a jet of compressed air into the casing

- to throw material that has been introduced into the casing against the said impact plate, a section blower adapted to maintain a pressure below atmospheric pressure in the casing,
- 5 and means for admitting scavenging air into the bottom of the casing under pressure.
3. An impact mill for disintegrating solid material, comprising a casing, an impact plate in the casing, a nozzle adapted to admit a jet of compressed air into the casing to throw material that has been introduced into the casing against the said impact plate, a suction blower adapted to maintain a pressure below atmospheric pressure in the casing,
- 10 and means for admitting scavenging air into the bottom of the casing tangentially under pressure.
- 15 4. An impact mill for disintegrating solid material, comprising a closed casing having an inlet for admitting material to be disintegrated thereto, a nozzle arranged to admit a jet of compressed air into said casing, an impact plate arranged in the casing in a position to be impinged by the jet of air issuing
- 20 from the nozzle and the material carried along with the air, the portion of the interior of the casing in the vicinity of the impact plate constituting a disintegrating zone, and suction means in communication with the
- 25 disintegrating zone for removing the disintegrated material and maintaining the interior of the casing at sub-atmospheric pressure, the inlet for the material, the impact plate and the disintegrating zone being located in the upper part of the casing.

In testimony whereof I have signed my name to this specification.

LUDWIG KOLLBOHM.
